DESIGN FOR A MUFF

Thomas L. Vine, New York, N. Y.

Application December 16, 1943, Serial No. 112,013

Term of patent 14 years

(Cl. D3—2)

To all whom it may concern:

Be it known that I, Thomas L. Vine, a citizen of the United States, residing at New York, in the county of New York and State of New York, have invented a new, original, and ornamental Design for a Muff, of which the following is a specification, reference being had to the accompanying drawing, forming a part thereof, wherein:

Fig. 1 is a front view of a muff showing my design;

Fig. 2 is a side view thereof.

The essential characteristics of the design are shown in full line drawings.

I claim:

The ornamental design for a muff, as shown and described.

THOS. L. VINE.
